TAPE DISPENSER

Davis Marinsky, Bronx, N. Y.; Louis H. Morin
executor of estate of said Davis Marinsky, deceased

Application December 14, 1946, Serial No. 716,363

9 Claims. (Cl. 164—47)

1

This invention relates to spools of tape of various kinds and classes. More particularly, the invention deals with a dispenser in the form of a casing in which the spool is adapted to be arranged, the casing having a spring actuated cutter mounted thereon to facilitate severing of a withdrawn length of the tape, and at the same time, rendering a tape end accessible for withdrawal of additional tape as and when required. The novel features of the invention will be best understood from the following description when taken together with the accompanying drawing in which certain embodiments of the invention are disclosed, and in which the separate parts are designated by suitable reference characters in each of the views, and in which:

Fig. 1 is a perspective view showing one of my improved devices arranged upon a tape spool; and

Fig. 2 is a section substantially on the line 2—2 of Fig. 1, showing only a part of the construction and with parts in different position in full lines and in the position shown in Fig. 1 in dotted lines.

In Fig. 1 of the drawing I have shown at 10 a spool of adhesive or other tape, a tape end being shown at 11 in said figure. At 12 is shown a cup or disk-shaped casing in which the spool 10 is mounted, the casing having at one edge a slot or opening 13 facilitating the threading of the tape into an aperture 14 formed in the peripheral wall of the casing 12. The slit 13 is preferably positioned at a point forwardly of a cutter 15 when the cutter is in retracted position, as shown in full lines in Fig. 2 of the drawing. The casing 12 at one side of the aperture 14 is provided with a fingerpiece opening 16 spaced from the aperture 14 by a transverse strip 17 which forms a platform upon which the adhesive side of the tape 11 is temporarily secured after a tape end has been severed, as later described.

Secured to the casing 12 at the other side of the aperture 14 is a plate 18 having at one end a raised ear or lug 19, and at the other end an outwardly pressed stop portion 20. The plate is provided with an elongated opening 21 centrally and longitudinally thereof. Slidably mounted in the plate 18 and on the periphery of the casing 12 is the curved cutter 15, the curvature of which conforms to the curvature of the casing. The cutter 15 has at its inner end an outwardly extending lug or fingerpiece 22 to which is secured a pin 23 upon which one end of a coil spring 24 is mounted. The other end of the spring is secured in any manner to the lug 19. The spring 24 is tensioned to normally

2

support the cutter 15 in the full line position shown in Fig. 1, and the dotted line position shown in Fig. 2. The other end of the cutter 15 has an enlarged blade portion 25 having a saw-tooth cutter edge 26 which is greater in width than the width of the aperture 14 and opening 16, so that the enlarged end 25 freely slides over the casing and is guided by the walls of the casing.

10 In the normal position of the cutter 15, the edge 26 is disposed at a point beyond the cross-piece or platform 17 and over the finger opening 16, as clearly seen in dotted lines in Fig. 2 of the drawing. It will thus be apparent that 15 when the cutter is retracted to the full line position of Fig. 2, the end 21 of the tape is disposed over the opening 16 and may be freely grasped by the fingers of a hand, to pull the tape outwardly first in removal from the platform 17 and then 20 to withdraw the tape from the spool, as is indicated in dot and dash lines at 28 in Fig. 2.

When the required length of tape has been withdrawn, with the cutter retained in the retracted position by the thumb engaging the fingerpiece 22 and a finger engaging the lug 19, the fingerpiece 22 is released, and the spring will advance the cutter forwardly. Upon completion of this operation, the tape will be partially severed by the cutter edge 26 and can be readily torn 30 off.

In the above operation, the withdrawn tape is held taut to enable the cutter edge to at least partially penetrate the tape. With some types and kind of tapes, the cutter may actually sever 35 the tape in the aforesaid movement. It will also be understood that the cutter automatically folds the tape upon the platform 17, thus again securing the same thereto and leaving another tape end 21 exposed for engagement by the 40 fingers of a hand when it is desired to withdraw another length of tape.

In the accompanying drawing, the plate 18 is shown as secured to the casing 12 by rivets, as at 29, but any form of fastening can be employed. 45 It will be understood that the offset portion 20 serves to guide the shank 30 of the cutter in its movement on the casing and the cutter is further guided by the lug or fingerpiece 22 operating in the aperture 21. It will also be apparent that 50 the casing 12 will be constructed to suit spools of various kinds of tape which are of standard sizes. In referring to sizes, reference is had to spool diameters, as well as tape widths. When 55 the tape of one spool has been consumed, a new spool may be inserted in the casing.

Having fully described my invention, what I claim as new and desire to secure by Letters Patent is:

1. A tape dispenser comprising a casing with which a spool of tape is detachably mounted, the casing having a peripheral wall encircling the spool, said wall having spaced openings between which is a tape engaging platform, the tape from the spool arranged in the casing being adapted to be drawn through one of said openings, a cutter movable circumferentially of the wall of the casing toward and from said openings, and said cutter having a cutter edge adapted to engage and sever tape withdrawn from the casing at a point beyond and in spaced relation to the platform and over the other of said openings, leaving a tape end exposed at the second opening beyond said platform for engagement by the fingers of a hand.

2. A tape dispenser comprising a casing with which a spool of tape is detachably mounted, the casing having a peripheral wall encircling the spool, said wall having spaced openings between which is a tape engaging platform, the tape from the spool arranged in the casing being adapted to be drawn through one of said openings, a cutter movable circumferentially of the wall of the casing toward and from said openings, said cutter having a cutter edge adapted to engage and sever tape withdrawn from the casing at a point beyond the platform and over the other of said openings, leaving a tape end exposed at the second opening for engagement by the fingers of a hand, said cutter being manually moved in one direction to expose the first opening for withdrawal of tape from said spool, and a spring for moving the cutter in the opposite direction.

3. A tape dispenser comprising a casing with which a spool of tape is detachably mounted, the casing having a peripheral wall encircling the spool, said wall having spaced openings between which is a tape engaging platform, the tape from the spool arranged in the casing being adapted to be drawn through one of said openings, a cutter movable circumferentially of the wall of the casing toward and from said openings, said cutter having a cutter edge adapted to engage and sever tape withdrawn from the casing at a point beyond the platform and over the other of said openings, leaving a tape end exposed at the second opening for engagement by the fingers of a hand, said cutter being manually moved in one direction to expose the first opening for withdrawal of tape from said spool, a spring for moving the cutter in the opposite direction, and means for keying and guiding the cutter in its movement on said casing.

4. A tape dispenser comprising a casing with which a spool of tape is detachably mounted, the casing having a peripheral wall encircling the spool, said wall having spaced openings between which is a tape engaging platform, the tape from the spool arranged in the casing being adapted to be drawn through one of said openings, a cutter movable circumferentially of the wall of the casing toward and from said openings, said cutter having a cutter edge adapted to engage and sever tape withdrawn from the casing at a point beyond the platform and over the other of said openings, leaving a tape end exposed at the second opening for engagement by the fingers of a hand, said cutter being manually moved in one direction to expose the first opening for withdrawal of tape from said spool, a spring for moving the cutter in the

opposite direction, and the casing having a slit registering with the first opening to facilitate threading of the tape into said opening.

5. A tape dispenser comprising a casing with which a spool of tape is detachably mounted, the casing having a peripheral wall encircling the spool, said wall having spaced openings between which is a tape engaging platform, the tape from the spool arranged in the casing being adapted to be drawn through one of said openings, a cutter movable circumferentially of the wall of the casing toward and from said openings, said cutter having a cutter edge adapted to engage and sever tape withdrawn from the casing at a point beyond the platform and over the other of said openings, leaving a tape end exposed at the second opening for engagement by the fingers of a hand, said cutter being manually moved in one direction to expose the first opening for withdrawal of tape from said spool, a spring for moving the cutter in the opposite direction, the casing having a slit registering with the first opening to facilitate threading of the tape into said opening, and the width of the end of the cutter having said cutting edge being greater than the width of said first named openings.

6. A tape dispenser comprising a casing having a circumferential wall portion, a cutter device, means on the wall portion and said device for guiding and keying the device for controlled movement circumferentially of the wall portion within predetermined limits, a spring normally supporting the device in extended position with the end of the device over a finger opening in said wall portion, another opening in the wall portion inwardly of said finger opening and separated therefrom by a tape engaging platform, and said cutter device being adapted for manual movement against the action of said spring to a position exposing the second opening in withdrawal of tape from said second opening.

7. A tape dispenser for mounting upon a tape spool, said dispenser comprising a casing in which a spool is adapted to be arranged, the casing having a peripheral wall encircling the spool, said wall being apertured for withdrawal of tape from a spool therethrough, means comprising a plunger type cutter movable circumferentially of said wall for severing a withdrawn length of tape, and said cutter supporting the severed end of the tape at a point beyond the limits of said opening.

8. A tape dispenser for mounting upon a tape spool, said dispenser comprising a casing in which a spool is adapted to be arranged, the casing having a peripheral wall encircling the spool, said wall being apertured for withdrawal of tape from a spool therethrough, means comprising a plunger type cutter movable circumferentially of said wall for severing a withdrawn length of tape, said cutter supporting the severed end of the tape at a point beyond the limits of said opening, and the casing having a fingerpiece opening at the severed end of the tape facilitating grasping of the tape end by the fingers of a hand when said cutter is retracted to free said tape end.

9. A tape dispenser for mounting upon a tape spool, said dispenser comprising a casing in which a spool is adapted to be arranged, the casing having a peripheral wall encircling the spool, said wall being apertured for withdrawal of tape from a spool therethrough, means comprising a plunger type cutter movable circumferentially of said wall for severing a withdrawn length of tape, said cutter supporting the severed end of the tape at

a point beyond the limits of said opening, the casing having a fingerpiece opening at the severed end of the tape facilitating grasping of the tape end by the fingers of a hand when said cutter is retracted to free said tape end, and said first named means comprising a spring for actuating the cutter in the first named direction.
